TOOL FOR CONCRETE FORMWORK

Thomas S. Thomsen, Kansas City, Mo.

Application July 24, 1935, Serial No. 32,892

4 Claims. (Cl. 254—79)

The present invention relates to tools for use in cement and concrete construction work, and the primary object in view is to devise an efficient hand-operated tool for the manipulation of the metal straps or bands which are employed for securing together the different parts of the formwork ordinarily required in such cement and concrete construction.

Accordingly I have devised an extremely simple and practical tool which is effective for such operations as are required of the workman for the convenient application and tightening and otherwise handling of these metal tie-straps or bands.

15 A further object of the invention is to provide such hand-operated tool with an attachment or accessory in the form of a bracing device adapted to serve as a means for temporarily steadyng or supporting the tool as required for some operations.

20 It is further sought to provide a tool structure which will be of a strong and efficient character, but of such simple design as to be inexpensive and economical to manufacture, and having few parts with practically nothing to get out of order.

25 With the foregoing general objects in view, the invention will now be described by reference to the accompanying drawing illustrating a practical form of the improved tool, after which those 30 features and combinations deemed to be novel and patentable will be particularly set forth and claimed.

In the drawing—

35 Figure 1 is a perspective view showing a portion of a formwork, and the improved tool also shown in operation for tightening a metal tie strap or band to be nailed upon said formwork;

Figure 2 is a horizontal sectional view, representing a section taken on the line 2—2 of Figure 1;

40 Figure 3 is a similar view, but illustrating a different mode of use of the improved tool;

Figure 4 is an enlarged detail sectional view of the head portion of the tool;

45 Figure 5 is a sectional view,—representing a section taken on the line 5—5 of Figure 4; and

Figure 6 is a perspective view similar to the view shown in Figure 1, but showing the tool provided with an accessory device in the form of a prop or bracing attachment, for adjustably supporting the tool in certain of its operative positions while in use.

Referring now to the drawing in detail, the use of the improved tool is illustrated in connection 55 with the work for which it is most specially

adapted, i. e., in connection with the application, tightening and fastening of the metal tie straps or bands 10 required for fastening together the various frame members 12 used in constructing the formwork.

5 The tool itself comprises a head-piece of tool steel, the opposite sides 14 of which are formed with spaced pointed terminals or prongs 15 which are provided with alined chisel edges 16 for form-engaging purposes. The opposite sides 10 14 of the head-piece are connected by a transverse element such as a block 18 formed with a threaded passage 19 for a screw-threaded rod 20; the outer end of this rod is provided with a suitable operating handle 22, while its other end 15 is pointed, as indicated at 24, for cooperation with a suitable opening 25 which is formed in another transverse element such as a connecting plate or bar 27 also located between said side portions 14 in spaced relation to the block 18 and presenting said opening 25 in alinement with the central point 24 of the rod 20.

20 The spaced relationship of the block 18 and the plate or bar 27 also provides a passage 28 through which to thread the ends of the straps or bands 10, to which the tool may then be securely clamped at any desired point by the operation of the screw-threaded rod 20 for that purpose, as illustrated in Figures 1 to 3, which operation produces a punch-like action as the pointed 25 end of said rod jams the metal of the band into the opening 25. Figures 1 and 2 illustrate the operation in relation to the formwork 12 of a pillar or column; the tie straps or bands are nailed (as indicated at 30) at one end and then, 30 being clamped within the head-piece of the tool as just described, may be drawn and tightened with a powerful pulling action by a prying operation of the tool, in the manner illustrated.

25 This drawing and tightening operation is carried out by jabbing the biting or chisel edges 16 of the prongs 15 into the woodwork of the form structure and then exerting a prying action by means of the tool to whatever extent is necessary for producing the desired strap-tightening 35 effect, preparatory for the nailing of the remainder of the strap or band to the form. If any difficulty should be experienced in causing the chisel edges 16 to bite into the form (due to hardness of the wood, for example), the workman can deliver a hammer blow upon the outer end of the rod 20, or preferably upon the blunt 40 ends of the sides 14 of the head-piece, for driving the prongs 15 and thereby causing the said 45

edges 16 to pierce into the wood for effectively anchoring the tool.

A different mode of connecting the tool with the strap ends may be employed, as illustrated 5 in Figure 3 in relation to the form structure for a beam. In this case, the end of the strap or band 18 is threaded through the passage 28 from the opposite direction before being clamped by the pointed end of the rod 20. By this means a 10 still more powerful drawing and tightening action may be exerted by the tool's lever action,— the strap being even more securely held, and the operating length or leverage of the tool being also greater, due to the strap passing beneath 15 the bar 27 and between the prongs 15. This may be found particularly desirable in connection with heavier work, using heavier ties or bands, or in some cases a plurality of straps or bands may be used and fastened at one and the same 20 time for purposes of greater strength, and stronger anchorage effect.

In Figure 6 the tool is illustrated as provided with an accessory or bracing attachment for facilitating the use of the tool in the manipulation 25 and fastening of the straps or tie bands 18 by a single operator or workman.

This accessory or attachment comprises a pair of links 32, 33, pivotally connected at 34. The outer end of the link 32 is provided with a yoke 30 32' pivotally connected at 35 to a collar 36 adapted to be slidingly mounted upon the screw rod 20 for movement toward or from a stop pin 37 which is fitted to said rod. The outer end of the link 33 is formed with a pair of prongs 18' 35 having alined chisel edges 16' similar to the prong construction already described as a part of the tool head-piece. The link 33 is also provided with a stop lug 38 for limiting the straightening movement of the links, and preferably the 40 pivot 34 is provided with a handle 39 for convenience in operating and adjusting the attachment.

It will be apparent that with this accessory construction, on operating the tool for drawing 45 up and tightening the strap 18, the attachment may be conveniently manipulated to brace the tool in the position into which it has been operated to hold the strap, and so hold the tool in such position while the workman may have the 50 free use of both his hands for the work of punching and nailing the strap before it is released from the grip of the tool.

In both instances of the use of the chisel edges 16 and 16', there is the decided advantage of 55 effectively preventing any casual rotative tendency of the tool, so that the same maintains its position against any influence tending to swing it out of any given operative position.

It will therefore be seen that an extremely 60 simple and yet efficient form of tool and accessory or attachment have been devised for the carrying out of the aforesaid objects of my invention. The construction may of course be carried out to any size necessary for meeting the 65 requirements of any special conditions, and for exerting any necessary mechanical effort required for the drawing up and tightening of the straps or bands. While the tool proper, as shown, may be handled and operated to a certain de-

gree, in most of its operations, without the accessory or attachment, by means of a single workman, the provision of said attachment facilitates in a marked manner the handling and operation of the tool by one workman by virtue 5 of the bracing and supporting function provided by such bracing and holding attachment, and thus in a very great degree promotes the ease and convenience of the work of the operator, and to a like extent increases the utility 10 of the device.

While I have herein described and illustrated what I have found to constitute a satisfactory and efficient embodiment of the improvements comprising my invention, I desire to be understood as reserving the right to make whatever changes and modifications may be deemed to fairly fall within the scope of the appended 15 claims.

What I claim is:—

1. A tool for formwork, comprising a head-piece provided with spaced prongs formed with alined chisel edges, means providing a strap or band passage through said head-piece, and means for clamping said strap or band with a 25 punching action within said passage, said last means including a rod forming a handle for producing a prying action upon the band or strap by a fulcruming movement of the tool upon said chisel edges.

2. A tool for formwork, comprising a head-piece provided with spaced prongs formed with alined chisel edges and also with spaced transverse elements providing a strap or band passage, one of said elements having an opening, 35 and a rod threaded through the other transverse element in alinement with said opening for clamping the bands or straps with a punching action, said rod forming a handle for producing a prying action upon the band or strap by a 40 fulcruming movement of the tool upon said chisel edges.

3. A tool for formwork, comprising a head-piece provided with spaced prongs formed with alined chisel edges and also with spaced trans- 45 verse elements providing a strap or band passage, one of said elements having an opening, and an elongated rod threaded through said other element and formed with a pointed terminal for cooperation with said opening for 50 clamping the bands with a punching action, said rod projecting beyond said head-piece and in alinement with said space between said prongs to provide a handle for producing a prying action upon the bands or straps by a fulcruming move- 55 ment of the tool upon said chisel edges.

4. A tool for formwork, comprising a head-piece provided with spaced prongs for engagement with the formwork, means providing a strap or band passage through said head-piece, 60 a rod operative for clamping the strap or band within said passage, a pair of toggle links forming a bracing attachment for holding the tool in strap-tightening position, one of said links having prong terminals for engagement with 65 the formwork, and means for slidingly connecting the other of said links with said rod.

THOMAS S. THOMSEN.
